UNITED STATES PATENT OFFICE.

FRANK C. REYNOLDS, OF COLUMBUS, OHIO, ASSIGNOR OF ONE-HALF TO HERBERT R. KUHN, OF COLUMBUS, OHIO.

CAR-COUPING.

970,553.

Specification of Letters Patent. Patented Sept. 20, 1910.

Application filed February 1, 1909. Serial No. 475,463.

To all whom it may concern:

Be it known that I, FRANK C. REYNOLDS, a citizen of the United States, residing at Columbus, in the county of Franklin and State of Ohio, have invented certain new and useful Improvements in Car-Couplers, of which the following is a specification.

My invention relates to the improvement of car couplers and has particular relation to that general form of coupler in which the Janney type of coupler head is employed.

The objects of my invention are to provide an improved construction of car coupler of this class in which the swinging of the knuckle to the open and closed positions, is accomplished without the employment of a knuckle or pivot pin and at the same time to construct a coupler which will have great strength and durability; to provide improved means for operating the knuckle locking mechanism and to produce other improvements the details of which will be more fully pointed out hereinafter. These objects I accomplish in the manner illustrated in the accompanying drawings, in which:

Figure 1 is a plan view of my improved coupler, Fig. 2 is a sectional view on line $x-x$ of Fig. 1, Fig. 3 is a reduced front elevation of the coupler showing the knuckle in the closed or locked position, Fig. 4 is a detail view in perspective of the knuckle and, Fig. 5 is a sectional view on line $y-y$ of Fig. 1.

Similar numerals refer to similar parts throughout the several views.

In carrying out my invention, I employ a coupler head 1 of the well known Janney type, said coupler head being provided with the usual mouth or recess 2 and jaws 3 and 4, the jaw 3 being bifurcated to form jaw arms 3^a and 3^b . With the underside of the coupler head, I form a downwardly and rearwardly extending hook member 1^a. On the underside of the upper jaw arm 3^a , I form a plurality of downwardly projecting parallel ribs 5 which are curved to form arcs of circles, as shown more clearly in dotted lines in Fig. 1 of the drawing. Vertically opposite the curved ribs or projections 5, I form in the upper side of the lower jaw 3^b , correspondingly curved ways or recesses 6. In the rear portion of the coupler head body, I form a vertical rectangular opening 7 which is adapted to receive

a locking pin in the manner hereinafter described.

8 represents a knuckle body of a substantially U-form, the outer terminal member or tongue 8^a of which is of slightly greater height than the body of said knuckle, the rear side of the upward and downward extension of said tongue being curved, as shown more clearly in Fig. 4 of the drawing, at 8^b. In the upper side of the knuckle body 8, I provide a plurality of parallel curved grooves or ways 9, the outer or first of these ways leading into the body of the knuckle at a point in rear of its end tongue 8^a. In constructing the knuckle body I form the underside thereof, with downwardly projecting and curved ribs or tongues 10 which are arranged vertically beneath the grooves or ways 9 of the upper side of the knuckle. The inner end of the knuckle is formed with an angular end recess 8^c. Extending from the side of the knuckle body at a point near its inner or rear portion, is a curved pin or rod 11 which is adapted to receive a detachable head 12 at its outer end.

As indicated in the drawing, the grooved and tongued portion of the knuckle body is adapted to be movably supported within the bifurcation of the jaw 3 of the coupler head, the ribs or tongues 5 of the jaw arm 3^a entering and being loosely embraced by the grooves or ways 9 of the upper side of the knuckle and the tongues or ribs 10 of the underside of the knuckle engaging in a similar manner the grooves 6 of the lower jaw arm 3^b . The knuckle being in this position, the curved projecting pin 11 passes through an opening in the side of the coupler head and on the outer side of said coupler head, said pin passes loosely through an eye 13^a in the vertical intermediate portion of a lever 13. From its eye portion 13^a this lever extends upwardly and thence is inclined outwardly, said upward and outward extension being slotted lengthwise, as indicated at 13^b and in addition to said slot, being bifurcated vertically, resulting in the formation of parallel slotted arms 13^c. At the junction of the arms 13^c and the straight vertical portion of the lever 13, an outwardly projecting enlargement 13^d is formed, with which is pivotally connected, a normally vertical and longitudinally slotted bar or

link 14, the latter having at its lower end an outwardly projecting hook member 14^a which is adapted to engage the head or enlargement 12 of the pin 11. The lever 13 is 5 fulcrumed between ears or lugs 15 which project from the lower portion of the coupler head and from this fulcrum point, said lever is inclined downward and inward to form a substantially hook-shaped termination 13^c.
 10 16 represents a coupler operating rod, the inner enlarged bifurcated end of which is provided with a transverse pin 17 which passes through the slots 13^b of the members 13^c and also through the slot of the member 14.
 15 18 represents the knuckle locking pin which I employ, the body of said pin being rectangular in cross section. In its lower half, one side of the pin 18 is recessed as indicated at 18^a and the lower unrecessed end of the pin is slightly rounded, as shown in Fig. 2 of the drawing, and formed with a forward and lower side projection 18^b. The upper side of the recess 18^a is inclined 20 as indicated at 18^c. When the pin is completely inserted or in its lowest position within the pin opening 7, its curved under surface is designed to be supported upon the terminal member 13^c of the lever 13.
 25 30 It will be understood that through the medium of the sliding engagement of the curved tongues and grooves of the knuckle, and coupler head jaw arms, a swinging movement of the knuckle between said jaw 35 arms for the purpose of moving the knuckle to the open position shown in dotted lines, may be imparted thereto with the same effect as if said knuckle body was pivoted in the well known manner by a knuckle pin between said jaw arms. When the knuckle is 40 in the closed position shown in full lines in Fig. 1 of the drawing and the locking pin 18 is properly inserted within the opening 7, said pin engages the rear side and end recess 45 8^c of the knuckle tail and by such engagement the knuckle is prevented from being moved outward to the open position through strain of the knuckle of the adjoining coupler. When, however, it is desired to 50 open the knuckle to the position shown in dotted lines in Fig. 1, the operation consists in pulling outward upon the operating rod 16, thereby forcing the upper portion of the lever 13 outward and the lower portion 55 thereof inward and upward and causing a lifting of the locking pin until its lower end projection 18^b comes into frictional contact and is dropped into engagement with the upper side of the hook projection 1^a of the 60 coupler head.

As will readily be understood the result of a continued outward pull on the rod 16 must result not only in imparting an outward inclination to the slotted arms 13^c, but 65 through the traveling of the pin 17 through

said slots and through the slot of the member 14, in imparting an outward incline to the latter corresponding in inclination to the members 13^c. This outward swinging movement of the member 14 must result in an 70 inward movement of the hook end 14 of the member 14^a and in a consequent inward pressure on the pin 11 which moving through its guide opening in the coupler head, will result in turning the knuckle to 75 the open position shown in dotted lines in Fig. 1 of the drawing. When the knuckle is again swung inward to the closed position, it will be understood that the knuckle tail will come into contact with the inclined 80 upper end 18^c of the recess 18^a of the elevated locking pin and as the tail of the knuckle passes through the recess 18^a, its contact with the upper inclined end of said recess, will result in the pin 18 being lifted 85 sufficiently to disengage it from the hook 1^a, thereby permitting the pin to drop again into engagement with the rear side of the knuckle tail.

From the construction and operation described, it will be observed that the swinging movement of the knuckle is accomplished without the provision of a fixed pivot point for the knuckle and it will be readily understood, that the engagement of the 95 grooves and tongues will afford an exceedingly strong connection between the knuckle and coupler head, thereby permitting great strain on the knuckle without danger of breakage of the parts. It will also be observed that the unlocking of the knuckle and the throwing of the knuckle to the open position as soon as it is disengaged from the locking pin, is accomplished by a single continued pull on the operating rod, thus 100 providing a simple although positive means of releasing and forcing the knuckle outward.

What I claim, is:

In a car coupler, the combination with a 110 coupler head having a bifurcated jaw, of a coupling knuckle within said bifurcated jaw, and a plurality of curved concentric tongue and groove connections between said jaw and said knuckle, and means for locking 115 said knuckle in its closed position, said means comprising a member which lies in front of a portion of said knuckle to prevent swinging movement thereof, but which does not pierce said knuckle, the grooves of 120 the tongue and groove connections being continued entirely through said bifurcated jaw to permit the knuckle to swing entirely out of said jaw.

In testimony whereof I affix my signature 125 in presence of two witnesses.

FRANK C. REYNOLDS.
